UNITED STATES PATENT OFFICE.

DAVID F. DOODY, OF WASHINGTON, DISTRICT OF COLUMBIA.

DESIGN FOR A GAME BOARD.

Application filed March 31, 1925. Serial No. 12,964. Term of patent 3½ years.

To all whom it may concern:

Be it known that I, DAVID F. DOODY, a citizen of the United States of America, and a resident of the city of Washington, District of Columbia, have invented a new, original, and ornamental Design for a Game Board, of which the following is a specification, reference being had to the accompanying drawing, forming a part thereof.

The figure is a plan view of a game-board, illustrating my new and ornamental design.

I claim:

The ornamental design for a game-board, as shown.

DAVID F. DOODY.
